UNITED STATES PATENT OFFICE.

ERNEST D. GRADY, OF CHARLOTTE, NORTH CAROLINA.

ADDRESSING MACHINE.

Application filed October 12, 1926. Serial No. 141,112.

This invention relates to stencilling devices, or more particularly to a device for addressing envelopes, which device eliminates the need of an expensive machine for 5 this purpose and works very much on the same principle as the rubber stamp.

An object of my invention is to provide a stamp pad having a handle, with means for automatically picking up a stencil, holding the same while the stencil is being imprinted and automatically releasing the stencil after it has been used.

Another object of my invention is to provide a container for holding a plurality of 15 stencils with means on the container for operating mechanism located on a stamp pad.

Another object of my invention is to provide an addressing machine which can be used for addressing packages regardless of 20 the size of the packages.

Some of the objects of my invention having been stated, other objects will appear as the description proceeds.

In the drawings, I have shown a preferred 25 embodiment of my invention, in which—

Figure 1 is a perspective view of the upper portion of the container for holding the stencils and of the inking device and associated parts;

Figure 2 is a perspective view of the inking device and the stencil held in place ready for use;

Figure 3 is an enlarged detailed view of a portion of the inking device and of one of 35 the stencil containers with the mechanism in release position;

Figure 4 is a cross sectional view taken along the line 4—4 in Figure 1.

A brief description of the drawings having been given, a detailed description will now follow in which like reference characters indicate corresponding parts throughout the drawings.

The numeral 10 indicates a container for 45 holding a plurality of stencils 11. This container has a compression spring 12 mounted therein, the lower portion of which is secured to the bottom of the container (not shown). The upper portion of this spring 50 rests against a false bottom 13 on which the stencils 11 are adapted to rest. The strength

of this spring 12 is such that regardless of the number of stencils in the container at any time, the upper stencil will always be in the position indicated in Figure 1. The 55 upper portion of container 10 flares outwardly on the four sides, as indicated by the numeral 14 in Figure 1. Between these outwardly flaring members 14 and the inside walls of the container there are shoulder 60 portions 15 on which the outer edges 16 of the inking device is adapted to rest while the stencils are being picked up by said stamp pad member.

The inking device is indicated by the numeral 17 and has a handle 18. Inside of the inking device, is located the ink box 19, which has a plurality of layers of fabric 20, 21 and 22, in the bottom thereof, which regulates the passage of ink therethrough to the 70 stencil.

On one of the sides of the inking device, the switch member 23 is pivoted on the pin 24. This switch member has forked clamp members 25 and 26 located on its ends. 75 Mounted in a horizontal plane and equidistant from the pin 24, are the pins 27 and 28.

On the respective ends of the inking device are mounted the electro-magnets 29 and 30, the cores 31 and 32 of these electro-magnets 80 being approximately flush with the lower surface 16 of the inking device. Two electric wires 33 and 34 are led from a source of electric energy (not shown) through the handle member 18, the wire 33 85 being connected to the pin 28. The wire 34 is connected to wires 35 and 36, the wire 35 being connected to one of the terminals of the electro-magnet 29. To the other terminal of the electro-magnet 29, is connected the 90 wire 37, which leads to and is connected to the pin 24, and from this pin 24, a wire 38 leads to one of the terminals of the electro-magnet 30, and to the other terminal of the electro-magnet 30, there is secured the wire 95 36, which leads back and is connected to the wire 34.

Located in the ends of the stencil member 11 and on the upper surface, thereof, only, are the metallic contact points 39.

On the side of the container 10 and projecting upward from the surface 15, is the

pin 40 and located in like manner on the side of the container 41 is the pin 42.

The operation of my device is as follows:

Assuming that the parts are in the position as shown in Figure 1, with the wires 33 and 34 connected to a source of electric energy, the operator seizes the handle 18 and presses the inking device and the associated parts downward into the flaring top of container 10. When the inking device 17 enters the top of the container 10, the pin 40 will press the hook 26 upwardly, thereby causing it to firmly engage the pin 28, and at the same time the hook 25 will be forced out of engagement with the pin 27. In this position, the electro-magnets will become charged and the cores 31 and 32 of said electro-magnets, being in contact with the metallic points 39, will cause the stencil to be securely held against the inking device as shown in Figure 2. The device is now ready to be pressed against an envelope for addressing the same. As soon as the addressing operation is completed, inking device 17, while still holding the stencil is pressed downwardly into another container 41, which is a duplicate of the container 10, with the exception that the container 41 does not have a spring bottom, and with the further exception that the pin 42 is located at a point where it will press the hook 25 upwardly into engagement with pin 27, thereby releasing hook 26 from the pin 28 and breaking the circuit through the electro-magnets. The electro-magnets being de-energized by this operation, the stencil will be released from the inking device and will fall into the receiving container 41.

Although I have shown a device of this nature operated by electro-magnets, I desire it to be understood that instead of using electric means for holding stencils against the inking device that I may use vacuum cups, instead of the electro-magnets with a suction pipe leading therefrom, to a vacuum and with the lever 23 operating an air valve to cut the vacuum on and off from the vacuum cups.

Having thus described the preferred embodiment of my invention, I desire it to be understood that although specific terms are used, they are used in a generic and descriptive sense, and not for purpose of limitation, the scope of this invention is being set forth in the appended claims.

55 I claim:

1. An inking device having magnetic means for picking up and holding a stencil during a printing operation and additional means for causing the stencil to be released after the printing operation.

2. A printing device having magnetic means for automatically attaching a stencil to an inking device and holding the stencil in attached position, and means for automatically releasing the stencil after the completion of the printing operation.

65 3. In a printing device, the combination of a container having a compression spring in the bottom thereof, a series of stencils supported by the compression spring, metallic 70 points on the stencils, an inking device having means thereon adapted to be engaged by a portion of the container for automatically operating the means on the inking device to pick up a stencil from the container and to 75 hold the said stencil.

4. In a printing mechanism, an inking device having electro-magnets mounted thereon, a source of electric energy for charging said electro-magnets, a switch for controlling 80 the flow of electric energy to the said electro-magnets to cause the electro-magnets to pick up a printing member, hold the same during the printing operation, and release a printing member, after the printing operation has 85 been completed.

5. In a printing device, the combination of an inking device, electro-magnets mounted on the inking device, a switch for controlling an electric current to the electro-magnets, a 90 container adapted to hold a plurality of stencils having metallic contact points thereon, a projection on the container for operating the switch to a position to energize the electro-magnets, the metallic contact points on the 95 stencils being adapted to be engaged by the electro-magnets to cause the stencils to adhere to the inking device, a second container having a projection thereon for operating the switch to de-energize the electro-magnets 100 and to allow the stencil to fall into the container.

6. An addressing machine having in combination, a container having a plurality of stencils thereon, a second container, an inking 105 device adapted to fit into the top of the container, electro-magnets on the inking device, said electro-magnets being adapted to pick one stencil at a time out of the container and to hold the said stencil against the inking device until the inking device is placed in the top of the second container.

7. An inking device, electro-magnets, mounted on the inking device, electric wires leading to the electro-magnets, a switch on 115 the inking device for controlling the flow of current to the electro-magnets, said electro-magnets being adapted to attract and hold a stencil against the inking device, until the printing operation has been completed and to release the stencil after the printing operation has been completed.

8. In an addressing machine, the combination of a container, stencils in the container, metallic contact points on the stencils, an inking device, electro-magnets on the inking device, a switch pivoted at its center on the inking device and adapted to be swung into po-

sition to energize and de-energize the electro-magnets, a projection on the side of the container adapted to engage the pivoted switch and to move the same to a position where it
5 will energize the electro-magnets, whereby one of the stencils will be held against the electro-magnets and against the inking device.

9. In a device as set forth in claim 8, a second container having a projection thereon for engaging and swinging the pivoted switch to de-energize the electro-magnets and to permit the stencil to fall into the second container. ¹⁰

In testimony whereof I affix my signature.
ERNEST D. GRADY.
